UNITED STATES PATENT OFFICE.

WILLIAM J. LEWIS, OF SYRACUSE, NEW YORK.

POWER PRESS IRONER.

Application filed December 12, 1925. Serial No. 75,127.

This invention relates to improvements in press ironers, designed for use by laundries, tailors, and the like, and has for its object to provide a power operated machine, to take 5 the place of the common foot-power ironers, wherein live steam is employed directly for effecting the pressing and ironing, and wherein the heating of the movable presser-head and the stationary buck, is effected by 10 the exhaust from the main cylinder that operates the presser-head. A further object is to provide a novel and simple valve for controlling the admission of the steam to the main cylinder, the said valve also controlling 15 the flow of the exhaust steam from the main cylinder direct to the presser-head and thence to the buck, for suitably heating said parts, and for maintaining the presser-head and buck at substantially constant temperatures 20 without loss or waste, and thereby obviating the necessity of providing separate means for heating the pressing parts as well as separate means for controlling said heating; the said valve being designed especially 25 for producing a steam cushion by means of which the head is prevented from ascending and descending too rapidly or in a jerky manner. A further object is to provide a novel guard, which substantially surrounds 30 the head and buck like a cage, primarily for protecting the operator's hands from injury arising from accidental or careless contact with the heated pressing parts, the said guard being pivotally supported by the 35 frame of the machine and being operatively connected with said valve and serving as the sole means by which the operator controls the lowering and raising of the presser-head as well as the flow of the exhaust 40 steam towards the head and buck. The said guard furthermore is arranged to effect the locking of the head in the raised position for preventing the head from gravitating towards the buck in case the steam pressure 45 fails or is shut off. And a further object is to provide a novel locking means for the head which is arranged to gravitate towards the locking position, and which is elevated or released by the lowering of the 50 guard.

I attain these objects by the means set forth in the detailed description which follows, and as illustrated by the accompanying drawings, in which—

Figure 1 is a front side elevation of the

machine; showing the working parts in the position for effecting the pressing or ironing. Fig. 2 is a side elevation of the same; showing by full and dotted lines the pressing and the release position of the head and guard. Fig. 3 is an enlarged broken side view and partial central vertical section of the pressing cylinder and its controlling valve; the full lines in the section indicating the position of the parts when the presser-head is in full release. Fig. 4 is a side view of the bell-crank which connects the guard with the valve. Fig. 5 is a vertical cross-section, taken on line 5—5 of Fig. 3. Fig. 6 is a detail view of the locking dog. Fig. 7 is a sectional view taken through the piston and valve cylinders, to show the manner of operating the piston.

In the drawings, 2 represents generally 75 the frame of the machine, comprising upright rear portions 2', and a reduced forwardly projecting portion 2", which supports the usual buck 3, by means of an intervening pedestal 3'. The buck 3 may follow any of the well-known constructions and need not be described in detail, except to say that it is hollow and may be heated by steam or other medium. 4 is the movable head by which the pressing and ironing is effected, and is rigidly mounted on the forward end of a forked arm 4', so as to position the head directly over the buck during the pressing and ironing operations. The presser arm 4' is pivoted in the frame portions 2', preferably by means of similar 80 alining hollow axles indicated at 4^a and 4^b, in Figs. 1 and 2; the axles 4^a—4^b preferably comprising similar sections of pipes. The arm 4' extends rearwardly and downwardly from its pivots and its lower end is formed with a loop or eye 4^c to which a piston rod 5 of the main operating cylinder 5' is pivotally connected, by a pin 4^d. The outer end of the piston rod proper is fitted with one member 5^a of a universal coupling, which is pivoted to a second member 5^b, as best seen in Figs. 2 and 3, and the latter member being connected with the arm 4', by means of a short rod 5^c. The cylinder 5' is preferably disposed 90 at an angle to the horizontal, by means of a shelf or ledge 2^e, which is disposed at the proper incline for effecting connection with the pivot 4^d. Upon the rod 5 is mounted the usual piston 5^d, which is shown in Fig. 3 in 95 100 105 110

the position for moving and holding the head 4 in the release position, Fig. 3 and by the dotted lines in Fig. 2.

The cylinder 5' is preferably operated by steam obtained directly from a boiler (not shown), the steam being controlled entirely by a novel valve, which is preferably inclined like cylinder 5' and comprises a cylinder 6 having a valve chamber 6', and a superposed steam chamber 6^a, which receives the fluid pressure from the boiler by means of a pipe 6^b. The chamber 6^a is constantly charged with the live steam, and said chamber is also in constant communication with the chamber 6', by means of similar ports 6^c—6^d, which are preferably respectively disposed near the opposite ends of the cylinder 6, as shown in Fig. 3. The flow of the steam towards the opposite ends of the main cylinder 5' is controlled by valves, as 6^e, which are mounted upon a common rod 6^x, whose outer end is operatively connected with a bell-crank 7, the latter being pivoted to the frame portion 2', by a bolt 7'. An arm 7^a of the bell-crank is pivoted to one member 8 of a universal coupling, the second member 8' being rigid on the outer end of rod 6^x. The rocking of the bell-crank moves the valves 6^e in the direction for supplying steam to the upper end of cylinder 5', for raising the head 4 away from the buck 3. When the valves 6^e are reversed, the steam flows from chamber 6' via a pipe 5' to lower end of cylinder 5', and moves the head 4 towards the buck 3.

The head and buck are preferably heated by the exhaust from cylinder 5', which alternately flows back from the opposite ends of cylinder 5' to chamber 6' via the pipes 5^e—5^f, as will be understood by the full and dotted positions of valves 6^e in Fig. 3. When the exhaust returns to chamber 6' by either of said pipes it flows out again via a relatively small port 6^y, and a pipe 9, the latter delivering the exhaust to the hollow axle 4^a from which a pipe 9^c carries it into the head 4. The exhaust circulates around the interior of the head, in a well-known manner, and escapes via a pipe 9^a, thence through the axle 4^b and a pipe 9^c to the buck 3. From the buck the exhaust flows via a pipe 9^c, in a more or less advanced state of condensation, to a trap 10, that collects the water of condensation and discharges it into a pipe 10', which preferably carries the waste heating fluid back to the boiler (not shown). This means for heating the head and buck by the exhaust, effects a great saving of steam, simplifies the working and controlling parts of the machine, cheapens its operation, and besides renders the heating of the pressing elements and the disposal of the condensation entirely automatic—no valves, levers, nor other parts that require attention or operation by the machine attendant being necessary.

The condensation or drip from cylinder 5' is carried to trap 10, by means of a T 9^x and a pipe 10^b. By providing the relatively small outlet 6^y, the drawing off of the exhaust from the cylinder 5', is so gradual as to effect a constant cushioning, which obviates all vibration, jerking and pounding of the head during its upward and downward strokes. This is very important and desirable, because the head is constantly under sufficient tension to render its operation steady and noiseless, which prolongs the life of the mechanism, thereby enabling it to perform more reliable and effective work, besides affording a better safeguard for its attendants. The size of the port 6^y, may be varied to suit different grades of work and to effect different speeds of travel of the head 4, but in either case should be smaller than the ports 6^c—6^d.

12 represents a cage-like guard, which conforms generally to the plan of the head and buck, and is composed of upright ribs 12', to which are secured a number of spaced horizontal guard-bars or slats 12^a, the latter being curved at their opposite ends for shielding the ends of the head and buck. The guard 12 is employed for the safety of the operator, in that it protects his hands from contact with the heated head and buck. The guard also serves the useful purpose of affording novel and simple means for controlling the valve 6, and supplants the usual pedals, operating levers and like parts heretofore employed for the purpose. The guard 12 is mounted upon the forward end of a lever or arm 12^b which is also pivoted on the axles 4^a—4^b, preferably outside of the arm 4' that supports the head. The rear end of the lever 12^b is fitted with a counterweight 12^c which substantially balances the guard, and with a perforated lug 12^d, to which is pivoted a link 7^x, that extends downwardly and is pivoted to an arm 7^b of the bell-crank 7. By this arrangement of the parts, the raising and lowering of the guard sets in motion the main operating pistons 5^d, for effecting the raising and lowering of the head 4, as described. By this use of the guard 12, no other lever or means is required for manually operating or controlling the power driven parts. To start the pressing or ironing operation, the operator pulls downwardly on the guard, by means of a handle 12^d, and as the guard approaches the end of the stroke, the steam carried by chamber 6' discharges into the lower end of cylinder 5' through pipe 5', and moves the piston 5^d in the direction for lowering the head 4 toward the buck 3, for effecting the pressing.

13 represents a member which is employed for automatically locking the head 4 in the elevated or released position for preventing its accidental descent in case the steam pres-

sure fails or is shut off. The locking member 13 comprises an elongated bar or part, one end of which is pivoted to the frame portion 2', by means of a bolt 13'. The opposite 5 end of said member comprises a hook 13^a, which is arranged to gravitate into the path of the projecting end of the pin 4^d, which pivots the piston rod 5 to the arm 4' (see Figs. 2 and 3). The locking member 13 is 10 controlled by an arm 7^c of the bell-crank 7, which is in constant engagement with a pin 13^b carried by said member. The arrangement of the locking member 13 is such that during the initial downward movement of 15 guard 12, the latter rocks the bell-crank in the direction for lifting the hook 13^a clear of the pin 4^d, an instant before the head starts its downward or pressing movement. The member 13 is then held released as long 20 as the head 4 remains on the buck (see Figs. 2, 3, and 6). When the pressing is done, the operator lifts the guard 12 toward the dotted position, shown in Fig. 2. This rocks the bell-crank 7 in the opposite direction and 25 allows the member 13 to gravitate into the path of the pin 4^d an instant before the said pin swings inwardly, as from the full line position of Fig. 2 to the position shown in Fig. 3, and when the pin 4^d finally makes 30 frictional contact with hook 13^a, it lifts the member 13, sufficiently to pass beneath the said hook. Member 13, then gravitates to the locking position, and holds the head 4 elevated, as shown by the dotted lines in 35 Fig. 2. This lowering of member 13 to the locking position is timed to be effected by the initial upward movement of guard 12, which does not effect the release of the steam from the chamber 6' for raising the head 4, 40 until the guard approaches the end of its upward stroke, as explained.

The operator may arrest the downward or pressing movement of the head during any stroke and cause the head to return to the 45 release position by simply swinging the guard 12 upwardly for reversing the travel of the head, as described.

My power press ironer is extremely simple, and may be operated at less expense, 50 and by fewer parts than any other machine of the class known to me. The provision of the novel fluid pressure controlling valve 6, which is operated by the guard 12, and which is provided with the relatively small 55 exhaust port 6^y, which is expressly calculated for effecting a constant cushioning within the pressing cylinder 5', and chamber 6' of the valve, whereby the head 4 is caused to move upwardly and downwardly 60 at a constant predetermined speed, and is restrained from dangerous rapid or jerky movements during the pressing operations, tends to adequately safeguard the operator and prevents jarring and wearing of the 65 machine. I am aware that guards similar to

the part 12 have heretofore been used in connection with press ironers, but I am not aware that such guards have been employed as the sole means for starting, stopping and otherwise controlling the entire working 70 mechanism, as well as the heating and the scavenging of the head and buck. Furthermore, by my method of heating the pressing elements by utilizing the exhaust from the primary cylinder 5', I am able to greatly 75 simplify, as well as reduce the cost of operating the press, and at the same time eliminate a number of parts, including the multiple controlling means that require attention and care of the operators, and lowers 80 the production, of the older pressing machines.

Having thus described my invention, what I claim, is—

1. A clothes pressing machine including a 85 heated movable head and stationary buck, a steam cylinder for operating the said head, a manually rockable cage-like guard surrounding the head and buck, a valve for supplying steam to said cylinder, means operated by said guard to actuate the valve, and means controlled by said guard for locking the head in inoperative position.

2. A press ironer including a movable 90 head and a buck, a steam cylinder for operating one of said elements, means for controlling the steam comprising a valve, means for locking said element in inoperative position, a rockable guard for shielding the head and buck, and means actuated by the 95 guard to operate said valve and to control said locking means.

3. A press ironer comprising a movable 100 head and a buck, a steam cylinder for operating the head, means for locking the head 105 in inoperative position, a reciprocatable valve for controlling the flow of the steam to and from said cylinder, a rockable guard, means actuated by the guard for operating said valve and means actuated by the guard 110 for releasing the said locking means in advance of the downward movements of the head.

4. In a clothes pressing machine, the combination with the heated head and buck and steam actuated means including a cylinder for moving the head towards and from the buck, of a valve adapted to receive steam from a boiler, said valve comprising a steam chamber and a valve chamber, the said chambers being in constant communication with each other by means of unrestricted ports and the valve chamber being connected with the opposite ends of said cylinder, 115 a bell-crank for operating the valves, a guard for the head and buck operatively connected with said bell-crank, a locking member and means to actuate the locking member by said bell-crank.

5. A press ironer, comprising a movable 120

- 4
- head, a buck, a steam cylinder having a piston therein for operating the head, a control for said piston, comprising a chamber and a reciprocatable valve therein, said chamber communicating with the opposite ends of said cylinder and having a small port controlled by said valve adapted to restrict the flow of the exhaust from the cylinder, for preventing rapid and jerky movements of the head, and a rockable guard for the head and buck for operating said valve.
- 5 10 15 20 25 30 35
6. A clothes pressing machine comprising a movable head and a buck, a steam cylinder for actuating the head, a valve for supplying steam to said cylinder, said valve having a relatively small port adapted to effect the slow escape of the exhaust from said cylinder, means for locking the head in the elevated position, and a guard surrounding the head and buck adapted to be raised and lowered manually for effecting corresponding movements of the head, and means to connect said guard with said valve whereby upon lowering of the guard to release said locking member in advance of the downward movement of the head.
7. A press ironer, including a movable head and a buck, a steam cylinder having a piston therein for operating the head, a valve having a valve chamber provided with similar ports for supplying steam to the opposite ends of said cylinder and an outlet of less area than the said ports adapted to retard the flow of the exhaust of said cylinder for effecting the steady and noiseless

strokes of the head, a double valve in said chamber, the space between said valves being in constant communication with said outlet and alternately communicating with said ports for drawing the exhaust from 40 said cylinder, and a rockable guard protecting the head and buck and operatively connecting with said valves.

8. In a power press ironer, a head and a buck, means to operate the head, a guard 45 for the head, means operated by the guard for effecting actuation of the said head operating means, and means controlled by the guard for locking the head in inoperative position.

50 55

9. In a power press ironer, a head and a buck, means to operate the head, a guard for the head, means operated by the guard for effecting actuation of the said head operating means, and means controlled by the guard for locking the operating means of the head in inoperative position and for releasing the locking means to permit downward movement of the head.

10. In a power press ironer, a head and a 60 buck, means to operate the head, a guard for the head having a handle attached thereto for operation of the guard, and means operated by the guard for solely effecting both starting and stopping of the said head 65 operating means.

In testimony whereof I affix my signature.

WILLIAM J. LEWIS.
